(57) CLAIM

The ornamental design for a hair dye brush handle, as shown and described.

DESCRIPTION

FIG. 1 is a perspective view of the hair dye brush handle; FIG. 2 is a rear view of the hair dye brush handle, the front view being a mirror image;

FIG. 3 is a left side view of the hair dye brush handle; FIG. 4 is a right side view of the hair dye brush handle; FIG. 5 is a top plan view of the hair dye brush handle; and FIG. 6 is a bottom plan view of the hair dye brush handle; and,

FIG. 7 is a rear view of a brush embodying the hair dye brush handle, the bristles of the brush being shown in broken lines for illustrative purposes only and forming no part of the claimed design.
